UNITED STATES PATENT OFFICE

2,078,611

DIE CASTING MACHINE

Vladimir J. Sebek, Cicero, Ill.

Application July 29, 1935, Serial No. 33,721

5 Claims. (Cl. 22—69)

This invention relates to die casting machines and has particular reference to improved mechanism for feeding molten metal from a melting pot or other heated container to a suitable die or 5 mold with the aid of compressed air.

One of the objects of my invention is to provide a swingingly mounted ladle and manually operable means for dipping the ladle into the molten metal in the melting pot for charging the ladle 10 with the molten metal and counter-weighted means for moving and returning the ladle to operative position with its mouth accurately aligned with the gate or opening of a die or mold whereby compressed air may then be forced into the ladle 15 to deliver the charge of molten metal into the die.

Another object of my invention is found in the provision of an adjustable counter-weight for regulating the pressure with which the mouth or 20 nozzle of the ladle is brought into contact with the gate or die opening.

A further object of the invention is found in the provision of adjustable means for accurately and positively controlling the vertical alignment 25 of the discharge mouth of the ladle with the gate or die opening.

A still further object of my invention resides in the construction and arrangement of a mechanism embodying a single manually operable lever 30 for moving the charging ladle into filling position and counter-weighted means operable upon the release of said lever for raising the ladle and positively locking same in aligned position with the opening of the die or mold.

35 A further object of the invention is found in the arrangement of adjustable means for accurately controlling the lateral adjustment of the toggle locking means for the ladle so that the discharge mouth or nozzle of the ladle may be 40 squarely and tightly held against the opening into the die.

With the above and other objects in view, my invention consists in the novel combination, construction and arrangement of the parts and members shown in preferred embodiment in the attached drawing, described in the following specifications and particularly pointed out in the appended claims.

Referring to the illustrations:

50 Fig. 1 is a plan view of a portion of a die casting apparatus embodying my invention.

Fig. 2 is a vertical section taken on line 2—2 of Fig. 1, showing the discharging position of the ladle and also showing by dot and dash lines, the 55 charging or filling position of the ladle and mechanism therefor.

Fig. 3 is a sectional plan view on line 3—3 of Fig. 2.

Referring now to the illustrations in more detail, a molten metal pot 10 is provided which is

suitably held into position within the furnace 11 having a lining 12 of fire brick, or the like.

The gate-opening for the die or mold is indicated by 13.

The ladle or molten metal carrier 14 is provided with an inlet connection 14^A for compressed air and with a mouth or nozzle 14^B.

The upper part of the ladle 14 is also provided with an upwardly and forwardly disposed integrally cast arm 14^C having a connection on the shaft 15 which is provided with enlarged ends or rollers 15^A which are securely held and guided laterally in the recesses 16^A of an adjustably mounted U-shaped yoke 16 when the ladle is in discharging position at the die opening 13. 15

The yoke 16 is vertically adjustable by means of a screw 16^B which is mounted in the support 16^C and a lock nut 16^D is provided for the screw 16^B. The rear end of the yoke is slidably mounted on the guide 16^E. 20

At its upper and rear end, the ladle 14 is cast with a pair of hook-like ears 14^D which open on their lower sides for hook-support upon the lateral pin 17 which is pivotally carried within the lower ends of the links 18. The upper ends of the links 18 are rigidly fixed to the cross shaft 19 which is supported upon the cast-iron stands 20. 25

Supported in bearings 21 on the rear end of the furnace 11 is a shaft 22 which is operatively connected to the pin 17 by means of a toggle 30 which comprises a crank 23, one end of which is rigidly fixed to the shaft 22 and the other end of which pivotally embraces the pin 24. The pin 24 is pivotally connected to the pin 17 by means of a pair of links 25. 35

The bearings 21 for the shaft 22 and toggle are laterally adjustable by means of a screw 26 and stud bolts 27 to insure a tight and accurate engagement of the ladle mouth or nozzle 14^B with the die opening 13. 40

The ladle 14 is held in positive discharge position, as shown by the full lines of the illustrations by means of counter-weights 28 which are adjustably slidably mounted upon the outer ends of the bars 29, the inner ends of which are provided with recesses 29^A and adapted to receive in such recesses the rollers or ends 15^A at the upper end of the arm 14^C when the ladle 14 is moved to filling position. 45

The bars 29 are pivotally mounted on a shaft 30 which is supported at the upper ends of the stands 20. The bars 29 are also formed with upwardly extended portions 29^B having hook-like ends 29^C constituting stops which limit the downward movement of the ladle when such stops engage upon the top of the yoke 16. 55

The shaft 22 is extended on one side to provide a connection for the operating lever 31 which is rigidly fixed thereto.

In the illustrations, the ladle 14 is shown in op- 60

erative position to discharge its contents of molten metal through its nozzle 14^B into the die opening 13 and as above pointed out, the nozzle 14^B is held tightly against the die opening 13 by means 5 of the toggle at its rear end.

The nozzle 14^B is also held in proper or accurate vertical alignment with the die opening 13 through the instrumentality of the ladle arm 14^C and its cooperating supporting yoke 16. It is 10 readily apparent that the vertical adjustment of the nozzle 14^B may be controlled by the adjustment screw 16^B which controls the position of yoke 16.

The operation of filling the ladle 14 with the 15 molten metal in the pot 10 may be described as follows:

An upward movement of the free end of the operating lever 31 into the position shown by dotted lines in Fig. 2, will cause a break in the 20 toggle by reason of the upward movement of the crank 23 which is rigid with the operating shaft 22 and through the links 25 will cause a rearward movement of the ladle 14. In such initial rearward movement, the ladle nozzle 14^B will be 25 moved substantially laterally and downwardly away from the die opening 13. During such movement, the ladle 14 will be supported at its rear end upon the pivotally mounted links 18 and the upper end of the rear of the ladle will of 30 course move in a slight arcuate path about the pivot pin 19. The upward movement of the operating lever 31 will support the front end of the ladle in recesses 29^A of the bars 29 and will lift the counter-weights 28 on the opposite ends of 35 the bars 29 to the position shown in dotted lines in Fig. 2, and will cause a downwardly and rearwardly movement of the ladle 14 to the filling position shown by the dotted lines wherein the greater portion of the ladle 14 will be submerged 40 in the molten metal in the pot 10 to permit a flow of the molten metal into the ladle 14 through its nozzle 14^B. The toggle links 25 and crank arm 23 will assume the positions shown by the dotted lines when the ladle 14 is in its filling 45 position.

When the ladle 14 has been filled with the molten metal, the raised operating lever 31 may be gradually allowed to lower under the downward pressure of the counter-weight 28 and the 50 several parts and members will again be brought into the positions shown by the full lines in the drawing wherein the mouth or nozzle 14^B will be brought into accurate position against the die opening 13. The contents of the ladle 14 may 55 then be discharged through the nozzle 14^B into the die by compressed air passed through the ladle opening 14^A.

I claim:

1. In die-casting apparatus, the combination 60 of a molten metal container, a ladle having a discharge nozzle and adapted to be filled with molten metal from said container through said nozzle, a support mounted on said container and extending above said container, a pair of links 65 pivotally mounted on said support for pivotally supporting the rear end of said ladle, means pivotally mounted on said support above said container having a recess at one end thereof and a counter-weight at the other end thereof, an extension on the front end of said ladle, operable means on said container connected to said ladle and adapted upon movement in one direction 70 to resist the pressure of said counter-weight

and to cause a rearwardly and downwardly movement of said ladle into filling position within said container, the extension on the front end of the ladle being supported within the recessed end of said counter-weighted means during the 5 filling of said ladle, and a vertically adjustable stationary support mounted on one end of said container adapted to receive and support said ladle front extension during the discharging operation of the ladle, said counter-weighted means 10 tending to retain said ladle in raised position.

2. In die-casting apparatus as embodied in claim 1, and including an extension on said counter-weighted means adapted to engage said vertically adjustable stationary support on said container for limiting the uppermost movement and 15 position of the said nozzle to thus accurately align the discharge mouth of the nozzle with the inlet opening of the die.

3. In die-casting apparatus as embodied in 20 claim 1, and including a pair of spaced abutments on one end of said counter-weighted means cooperating with said vertically adjustable stationary support on said container for limiting the uppermost and lowermost movements and positions of 25 the said nozzle.

4. In die-casting apparatus, and in combination, a molten metal container, a ladle having a discharge nozzle, a pair of supports, one on each side of said container extending above the 30 top of said container, pivotal means supported on said supports for pivotally supporting the rear end of said ladle, a counter-weighted pair of arms pivotally supported on said supports above said 35 ladle, a counter-weight adjustably mounted on said counter-weighted arms, said counter-weighted arms being adapted to retain the forward or front end of said ladle in raised discharging position, an operating lever operatively connected to said ladle and adapted to be moved to resist 40 the pressure of said counter-weight to cause a rearwardly and downwardly movement of said ladle into filling position within said container, an extension rigidly connected to said ladle arranged to cooperate with said arms to support 45 the front end of said ladle on said arms during the filling operation thereof, and stationary means mounted on one end of said container adapted to receive said extension to thereby support 50 said ladle in discharging position.

5. In die-casting apparatus, and in combination, a molten metal container, a ladle having a discharge nozzle, a support on said container, pivotally mounted means supported on said support for supporting the rear end of said ladle, 55 a pair of counter-weighted arms pivotally mounted on said support above said ladle and arranged to support the front end of said ladle during its movement into and out of filling position, a lever operatively connected with said ladle and adapted upon movement in one direction to resist the pressure of said counter-weighted arms during the rearward movement and tilting of said ladle into filling position, a stationary seat mounted above said ladle on the structure of the apparatus, 65 an extension on the front end of said ladle adapted for support on said seat, and integral extensions of said arms having spaced abutments adapted to alternately engage opposite portions of said stationary seat for limiting the uppermost and 70 lowermost positions of the ladle.
